UNITED STATES PATENT OFFICE.

ERNESTINE RUSSELL, OF ENID, OKLAHOMA.

LIFE-PRESERVER.

1,074,817.

Specification of Letters Patent.

Patented Oct. 7, 1913.

Application filed August 26, 1912. Serial No. 717,175.

To all whom it may concern:

Be it known that I, ERNESTINE RUSSELL, a citizen of the United States, residing at Enid, in the county of Garfield and State of Oklahoma, have invented certain new and useful Improvements in Life-Preservers, of which the following is a specification, reference being had to the accompanying drawings.

10 The present invention relates to new and useful improvements in life preservers and having for its primary object to provide a device of this character with a plurality of water tight receptacles which are designed 15 for holding supplies of food and water in sufficient quantities to help sustain life for a certain period of time.

A further object of the present invention is to provide means for holding the life preserver upon the body of the person which will prevent the same from turning when in the water and also to present the receptacles contained therein for available use.

With the above and other objects in view, 25 this invention consists of the novel details of construction, combination, formation and arrangement of parts as will be hereinafter more fully described and particularly pointed out in the accompanying drawings, 30 in which—

Figure 1 illustrates a plan view embodying my invention. Fig. 2 is a vertical section through the same, and Figs. 3 and 4 illustrate sections through the receptacles as 35 removed from the life preserver.

Referring now more particularly to the drawings wherein corresponding parts are designated by like numerals throughout the several views, the numeral 1 indicates an ordinary cork life preserver which is provided 40 with a canvas cover 2 and having a cork filling 3.

Mounted within recesses formed within the body portion of the life preserver are a 45 pair of elongated receptacles, indicated by the numerals 3 and 4, which have a curvature to conform with the body portion of the float. Each of these receptacles are preferably made of aluminum designed to hold 50 supplies of food and water in sufficient quantities to help sustain the life of the person for several days. Each of the receptacles

are provided with openings whereby access may be gained thereto and the receptacle 3 is provided with a threaded cap 5 adjustably mounted within the said opening and has extending therethrough an aluminum stem 6. This receptacle is designed for holding water and the stem 6 has secured thereto a flexible tubing 7 which will prevent any water from entering the receptacle and also to provide means which is easily and readily accessible to the person. The opposite receptacle is designed for holding provisions, such as hard-tack, liquid beef extract, or any other condensed food, and has a spring actuated lid 8 mounted thereupon, which is also available to the person and water tight.

The inner periphery of the life preserver 70 is provided with diametrically oppositely disposed straps 9 through which extend a belt 10 which is provided with adjustable means so that it may be adjusted to fit the wearer. A pair of shoulder straps 11 are 75 secured to the body portion of the preserver which will obviously prevent the same from turning or shifting when in water and also hold the food retaining receptacles to the available use of the person. 80

It is obvious from the foregoing description taken in connection with the accompanying drawings that I have provided a life preserver which will be inexpensive in the cost of manufacture, strong, durable and efficient when in use, and it is to be understood that other minor details of construction, changes as to form and operation, may be resorted to that come within the scope of the present invention without departing 90 from the spirit thereof.

What I claim is:—

A life preserver comprising a cylindrical cover and a filling for the same, said filling having receptacle accommodating openings 95 formed therein, the long edges of which correspond to the curvature of the filling and cover, food receptacles of substantially rectangular form positioned in the receptacle accommodating openings, said receptacles fitting snugly within the openings and having their long edges curved to correspond with the long edges of the openings, the upper portion of the cover covering the upper 100

faces of the receptacles, said receptacles having threaded neck portions projecting through the upper portion of the cover, caps for closing the threaded neck portions projecting through the cover, a stem carried by one of the caps, means for securing the life preserver to the body of a person, and shoulder straps carried by the cover of the pre-

server to prevent the same from turning upon the wearer. 10

In testimony whereof I hereunto affix my signature in the presence of two witnesses.

ERNESTINE RUSSELL.

Witnesses:

GUY S. MAUATT,
J. N. KEYS.
